Allen Allen

ATTORNEY.

UNITED STATES PATENT OFFICE

HENRY HIGGIN, OF NEWPORT, KENTUCKY, ASSIGNOR TO THE HIGGIN MANUFACTURING COMPANY, OF NEWPORT, KENTUCKY, A CORPORATION OF WEST VIRGINIA

SCREEN FOR CASEMENT WINDOWS

Application filed September 20, 1928. Serial No. 136,684.

My invention relates to window screens and particularly to a novel window screen for a casement window.

In many types of modern house constructions, casement windows, which are usually permanently hinged to the frames in which they are mounted, are provided. The window frames are retained within the masonry of the house, and as the windows open outwardly, there is seldom any provision for window screens. It becomes particularly a problem with such types of casement windows, to provide sliding screens. When sliding screens are provided, horizontal guides or channels may be secured on the inner or room side of the window to the window frames and the window sill, but there remains the vertical side of the window opening, which is usually of rough plaster, with which the inside edge of the screen will not make a tight engagement, thereby leaving what may be called a light line.

It is the object of my invention to provide a sliding screen provided with novel means of covering up what would otherwise be a light line between the edge of the screen and the rough plastered wall. To this end I provide a channel member readily attachable to the edge of the screen frame, and insert therein preferably a strip of felt which may be held in place by a sliding member which may be inserted in the added channel.

Referring to the drawings in which I have shown my novel screen in position in an ordinary casement window frame:

Figure 1 is a perspective view of a corner of a window in which one of my novel screens has been inserted, with portions of the screen cut away to show the casement window structure.

Figure 2 is a sectional perspective view of a corner of one of my novel casement window sliding screens, taken along the lines 2-2 in Figure 3.

Figure 3 is a front elevation of my preferred type of sliding screen.

Figure 4 is a horizontal section taken along the lines 4-4 in Figure 1.

A window opening in the walls of a house is indicated with the outer masonry walls of

the house indicated at 1 and the inner plastered walls at 2. The frame 3 of the casement window is engaged in the outer masonry, as indicated at 4 in Figure 4. The casement window sash, illustrated at 5, is hinged as at 6 to the casement frame. The window sash will thus swing outwardly as indicated by the arrow in Figure 4. My new type of screen, which is generally indicated at 7, is mounted in horizontal channels 8, which engage the upper and lower part of the screen frame. The channels may be secured in position in any desired way. I have shown the lower channel 8 attached to the wooden sill 9 of the frame, though it is within the scope of mechanical skill to secure the bottom channel or guide directly to the casement frame. It will be observed that in such a type of construction, if the screen had no means of making a seal for the light line, that a light line would occur between the edge 10 of the screen frame and the plastered wall 11 of the window opening.

In order to cover the light line, I have secured to the outer edge of the screen frame, a channel 12. Within this channel I have secured a strip of felt 13 along a line medial of its length, and have fixedly held the strip of felt in place by a strip 14, which is slidably retained within the channel. I find it a convenient way to mount the strip of felt to start pulling a doubled fold of the felt within the channel, with the strip 14 started at the same time so that the strip is pulled into position during the insertion of the felt. When once in place, the inturned flanges of the channel piece 2 are hammered down to tightly hold the felt in position. I have shown both edges of the felt as extending out from the edge of the channel, which I find provides a very positive means of covering the light line. It is within the scope of mechanical equivalency however, to have only one edge of the felt extended. The use of rubber strips or other flexible material will also occur to those skilled in the art, as a substitute for the felt which I prefer to employ. It will also be within the scope of mechanical equivalency to provide other means of securing the flexible strip in position.

Having thus described my invention what I claim as new and desire to secure by Letters Patent is:—

1. In combination with a vertical edge portion of a horizontally slideable screen, means operatively connected with said edge extending beyond said edge of said screen, said means comprising a channel portion separately secured to said screen, and a strip of flexible material mounted within said channel.
2. In combination with a vertical edge portion of a horizontally slideable screen, means operatively connected with said edge extending beyond said edge of said screen, said means comprising a metallic strip formed so as to have a channel portion secured to said screen, and a strip of flexible material detachably mounted within said channel.
3. In combination with a vertical edge portion of a horizontally slideable screen, means operatively connected with said edge extending beyond said edge of said screen, said means comprising a channel portion secured to said screen, and a strip of flexible material detachably mounted within said channel, and said flexible material consisting of a piece of felt supported within said channel along its median line, with at least one edge thereof extending beyond the edge of said channel.
4. In combination with a vertical edge portion of a horizontally slideable screen, a channel portion secured to said edge, a strip of material which has slidingly engaged said channel, and a piece of flexible material retained along its median line within said channel between the walls thereof, and the slidably engageable strip with the edge of the material extending beyond the edge of said channel.
5. A device for attachment to a window screen frame comprising a metallic channel member with turned-over edges, a metallic strip and a piece of flexible material held within said channel member by said metallic strip, said turned over edges gripping said flexible material and said strip, and at least one edge of said flexible material projecting from said channel member.

HENRY HIGGIN.
